UNITED STATES PATENT OFFICE.

CHARLES K. GILES, OF CHICAGO, ILLINOIS.

WATCH-CASE PENDANT.

SPECIFICATION forming part of Letters Patent No. 357,195, dated February 8, 1887.

Application filed February 10, 1886. Serial No. 191,516. (No model.)

To all whom it may concern:

Be it known that I, CHARLES K. GILES, a citizen of the United States, residing at Chicago, in the county of Cook and State of Illinois, have invented a certain new and useful Improvement in Watch-Cases, which is fully set forth in the following specification, reference being had to the accompanying drawings, in which—

10 Figure 1 is a central sectional view of a construction embodying my invention, the winding stem or key being in its extreme inward position. Fig. 2 is a similar view showing the winding stem or key withdrawn; Fig. 3, an 15 elevation of the winding stem or key and its spring or brake detached, and Fig. 4 is a plan section, taken on the line xx , Fig. 3.

Like letters refer to like parts in all the figures of the drawings.

20 My invention relates to watch-cases, and more particularly to the construction of the pendant and winding-stem of that description of watches known as "stem-winding," its object being to provide a simple and efficient 25 means for holding the stem in any position in which it may be placed and preventing accidental movement of the same.

I will now proceed to describe a construction in which I have practically carried out 30 my invention in one form, and will then point out more particularly in the claims those features which I deem to be new and desire to protect by Letters Patent.

In the drawings, A represents a portion of 35 a watch-case, of any usual construction, and B the pendant thereof. This pendant is provided with the usual aperture, B', to receive the winding-stem, which aperture is preferably reduced at its inner end, thereby forming 40 a shoulder, b.

C indicates the winding-stem, which is screw-threaded at its outer end to receive the crown D, which fits over the end of the pendant, as shown. The inner end of the winding-stem is provided with any approved means 45 for connecting it with the watch-movement—such, for instance, as the square socket c, (shown in the drawings,) or the usual square pin.

50 It will be observed that the winding-stem is considerably less in diameter than the aperture of the pendant through which it passes,

and in order to guide the said stem and hold it properly in positions, I employ a hollow sleeve or block, E, of an external diameter 55 substantially equal to the diameter of the aperture in the pendant, within which it fits snugly, being secured in position in any suitable manner. In Fig. 1 of the drawings this sleeve is shown as held in position by means 60 of the ring F, the ends of which pass through the pendant and enter a groove, f, in the sleeve, thereby preventing any longitudinal movement of the same. In Fig. 2 of the drawings the sleeve is secured by means of a screw, 65 f', which passes through the pendant and into the sleeve. Any other suitable manner of securing the sleeve may be adopted. The lower portion of the sleeve is reduced in diameter to correspond to the reduced portion of the aperture 70 B' of the pendant, thereby forming a shoulder, f'', upon the sleeve, which rests upon the corresponding shoulder, b, of the pendant, thereby forming a seat for the sleeve.

The sleeve E surrounds the stem C, which 75 passes through the sleeve in such a manner as to be capable of a free longitudinal movement therein. This longitudinal movement of the stem is necessary, of course, in order to enable the stem to be withdrawn into the pendant 80 when it is desired to insert the watch-movement in the case or withdraw it therefrom. In order, however, to hold the stem in any position to which it may be moved, and prevent accidental displacement of the same, a brake 85 is necessary, and this I provide by means of a spring formed integrally with the sleeve E, and bearing upon the stem C in such a manner as to hold it by means of the frictional contact between the two in any desired position. This brake or spring is constructed by forming in the sleeve an L-shaped or similarly-shaped slot, e, thereby forming a tongue, E', which is elastic and bears upon the winding-stem, acting, by reason of its frictional contact, as a brake, in the manner hereinbefore described.

It will be observed that the construction just described is extremely simple and cheap, the parts being readily manufactured and easily 100 assembled, while at the same time the device is effective in its operation and durable. It is obvious, moreover, that various modifications in the details of construction may be made

without departing from the principle of my invention, and I therefore do not wish to be understood as limiting myself strictly to the precise details of construction hereinbefore set forth, and shown in the drawings.

Having thus described my invention, what I claim as new, and desire to secure by Letters Patent, is—

1. The combination, with the pendant and stem, of the sleeve secured within the pendant and surrounding the stem, the said sleeve being provided with the L-shaped slot *e* to form the spring-tongue *E'*, substantially as and for the purposes specified.

2. The combination, with the pendant and stem, of the sleeve *E*, surrounding the stem and arranged within the pendant, the said sleeve being provided with the groove *f* and the ring *F*, having its extremities arranged to engage with the said groove, substantially as and for the purposes set forth.

CHARLES K. GILES.
